DESIGN FOR PLEATED LEATHER TRIMMING OR SIMILAR ARTICLE

Vito Pallotta, Brooklyn, N. Y.

Application March 19, 1940, Serial No. 91,051

Term of patent 7 years

To all whom it may concern:

Be it known that I, Vito Pallotta, a citizen of the United States of America, residing in Brooklyn, city of New York, county of Kings, and State of New York, have invented a new, original, and ornamental Design for Pleated Leather Trimming or Similar Article, of which the following is a specification, reference being had to the accompanying drawing, forming part thereof.

The figure on the drawing is a plan view of a pleated leather trimming or similar article showing my new design.

My design comprises an inverted pleated leather trim having an inlaid braid strip arranged as shown.

I claim:

The ornamental design for pleated leather trimming or similar article, substantially as shown and described.

VITO PALLOTTA.
